ELECTRICAL MUSCLE STIMULATOR

John I. Moss, Skokie, and Vernon J. Marik, Glenview, Ill., assignors to Relaxacizor, Inc., a corporation of California

Filed May 26, 1960, Ser. No. 60,733

Term of patent 14 years

(Cl. D83—1)

FIGURE 1 is a front elevation view of an electrical muscle stimulator embodying our new design; FIGURE 2 is a top plan view thereof; and

FIGURE 3 is a left side elevational view thereof, a portion of the side being broken away to show the configuration of the control panel.

The right side elevation of the stimulator is substantially similar to the left side elevation of FIGURE 3. The rear of the stimulator is substantially plain with the exception of the lower rib extending thereacross and the projection adequately shown in FIGURES 2 and 3.

We claim:

The ornamental design for an electrical muscle stimulator, as shown and described.
